W. SCOTT.
TONE MODIFIER FOR PHONOGRAHS,
APPLICATION FILED OCT. 23, 1920.

Patented Oct. 25, 1921.

Inventor

W. Scott

By *Watson E. Coleman*
Attorney

UNITED STATES PATENT OFFICE.

WALTER SCOTT, OF SHERIDAN, WYOMING.

TONE-MODIFIER FOR PHONOCRAPHS.

1,394,646.

Specification of Letters Patent.

Patented Oct. 25, 1921.

Application filed October 23, 1920. Serial No. 418,989.

To all whom it may concern:

Be it known that I, WALTER SCOTT, a citizen of the United States, residing at Sheridan, in the county of Sheridan and State of Wyoming, have invented certain new and useful Improvements in Tone-Modifiers for Phonographs, of which the following is a specification, reference being had to the accompanying drawings.

10 This invention relates to attachments for phonographs, and particularly to means for modifying the tone, that is the sound issuing from the tone chamber or amplifier of a phonographic cabinet.

15 A further object is to provide a device of this character consisting of a frame supporting a plurality of closely adjacent coiled springs extending transversely of the direction of the sound waves acting to reduce the 20 grinding or scratching tone of the phonograph and to reinforce the tone waves.

Other objects will appear in the course of the following description.

25 My invention is illustrated in the accompanying drawings, wherein:—

Figure 1 is a vertical sectional view through a portion of a phonograph cabinet showing the tone chamber or amplifying chamber in section, and showing my device 30 in place therein, the device being shown in elevation;

Fig. 2 is a top plan view of the tone modifying device forming the subject matter of my invention;

35 Referring to these drawings, it will be seen that my attachment comprises two approximately triangular plates 10 and 11 disposed in spaced relation to each other and connected by means of three transversely extending rods 12 disposed at the corners of the triangular plates. These plates are 40 preferably formed with perforations 13. The plates are not disposed in parallel relation to each other but in a slightly convergent

45 relation, as illustrated in the plan view in Fig. 2 and each of these plates on two of its edge faces is formed with equi-distantly spaced prongs 14. Stretched between these prongs are a series of small contractile coiled 50 springs 15. These springs may be all of the same diameter and the same number of coils, or they may be of different diameters and of a different number of coils. Preferably the springs on one side of the toning device will

55 be relatively large and the springs on the

opposite side relatively small. Thus the springs on one side may have a diameter of approximately $\frac{1}{8}$ ", while the springs on the opposite side may have a diameter of twice or three times that, the larger springs having their convolutions relatively greatly separated. I do not wish to be limited to having the springs of a single size on each face of the device, but may use, as before stated, the series of springs of different sizes and different tensions and each capable of responding to and vibrating under a different tone.

In the use of this device, it is disposed within the tone chamber B of a phonographic cabinet A, as illustrated, with the relatively large springs disposed toward the outer end of the tone chamber B and the relatively small springs disposed toward the tone arm. This device is simply placed in the tone chamber, as illustrated, and approximately fills the space between the side walls of the tone chamber. The sound waves issuing from the tone arm into the tone chamber and passing through the tone chamber will strike these springs and set them into vibration, which will, I find, modify the vibrations and cause the various tones to be reinforced by the vibrations of the springs. At the same time I find that this device tends to modify and eliminate the grinding or grating noise which is such an unpleasant accompaniment of phonographic reproduction.

It will be obvious that the springs may be arranged so that certain springs will vibrate to one tone and certain other springs will vibrate to other tones so that there will be a sympathetic vibration of one or more of the springs which will reinforce the tones given off by the phonograph.

I do not wish to be limited to the exact construction illustrated, as this might be modified in many ways without departing from the spirit of the invention, but I have found this attachment particularly useful and effective as illustrated.

I claim:—

1. The combination with a phonograph having an amplifier constituting a tone chamber, of a supporting frame disposed within the amplifier, and stretched coiled springs attached to the frame and supported thereby, these springs being of different diameters and having a different number of coils.

- convolutions to the inch, the springs extending transversely of the path of movement of the sound waves through the amplifier.
2. A tone modifier for phonographs comprising oppositely disposed, spaced, triangular plates, and a series of coiled contractile springs stretched across the space between said plates and engaged with the edges of the plates on two sides of the triangle.
- 10 3. A tone modifier for phonographs comprising two triangular plates held in spaced relation to each other, the faces of said plates being adapted to rest upon the floor of a tone chamber, the other margins of the triangular plates having prongs projecting therefrom, and stretched coiled contractile springs extending across the space between the plates and engaged at their ends with said prongs,
- 15 the springs on one side of the triangular frame formed by said plates being of different diameter and having a different number of convolutions to the inch from the springs on the opposite side of said triangular frame.
4. A tone modifier for phonographs comprising two triangular plates held in spaced relation to each other, the faces of said plates being adapted to rest upon the floor of a tone chamber, the other margins of the triangular plates having prongs projecting therefrom, and stretched coiled contractile springs extending across the space between the plates and engaged at their ends with said prongs,
- 20 the springs on one side of the triangular frame formed by said plates being of different diameter and having a different number of convolutions to the inch from the springs on the opposite side of said triangular frame.
- 25 In testimony whereof I hereunto affix my signature.
- 30
- WALTER SCOTT.
